(57) **CLAIM**

The ornamental design for a tire, as shown and described.

DESCRIPTION

FIG. 1 is a front view of a tire showing my new design; FIG. 2 is a right side view thereof; and, FIG. 3 is a perspective view thereof.

A rear view, top view and bottom view are omitted since the rear view, top view and bottom view are identical to the front view;

A left side view is omitted since the left side view is a mirror image of the right side view.

1 Claim, 3 Drawing Sheets

FIG. 1

FIG. 2

FIG.3
